STRIP CIPHER DEVICE

John W. McClaran, United States Navy

Application November 28, 1932, Serial No. 644,723

7 Claims. (Cl. 35—2)

1

This invention relates to a device for coding and decoding messages and is of the type employing a plurality of strips each with one or more complete alphabets thereon arranged at random, all the alphabets on any strip having the same sequential order, and preferably with a different sequence of letters on the various strips.

It is the object of this invention to provide a machine of the character mentioned that is adapted to produce a large number of highly complex cipher combinations without any sequence in the arrangement of the letters that is discoverable by one who has not the key thereto.

With the above and other objects in view, the invention consists in the construction, combination and arrangement of parts as will be herein-after more fully described.

In the drawings:

Figure 1 is a perspective view of my invention; Figure 2 is a bottom plan view thereof;

Figures 3, 4 and 5 are respectively a top plan view, a side elevation and an end elevation of the means used for connecting the ends of the strips that carry the alphabet;

Figure 6 is a detail view of portions of an alphabet strip;

Figure 7 shows an interrupter for covering certain of the strips if desired;

Fig. 8 is a plan view of the invention, with parts broken away, illustrating the method of use.

The general construction of my invention is shown in Figures 1 and 2. Feet 10, which are preferably flexible rubber vacuum cups, carry a frame comprising longitudinal members 11 connected by a cross brace 12. Plate 13 has an upper bracket 14 secured to each of two corners and a lower bracket 15 fixed to each of the other two corners thereof, the brackets 15 being attached to members 11 and the brackets 14 being fastened to uprights 16 that are pivotally connected to the members 11 to permit the disconnection of member 16 from brackets 14 so the device may be folded.

At the lower end of plate 13 is a series of independently rotatable pulleys 17 mounted on a common shaft and each having an outwardly extending flange 18, preferably knurled, that may be grasped by the thumb and fore-finger of the operator to rotate the pulley. An equal number of pulleys 19, also independently rotatable, are disposed at the upper end of plate 13 with pulleys 19 aligned with corresponding pulleys 17, whereby a flexible strip 20 may be passed around the plate 13 and over a pulley at each end thereof.

Each strip 20 has on it, preferably two alpha-

2

bets in which the letters are in the same sequence, as shown in Figure 6. The ends of each strip are connected together by the connecting element shown in Figures 3, 4 and 5 that has a substantially tubular body portion 21 in which is formed a longitudinal slot 22. A hook 23 is connected to spring 24 in the body 21 which tends to draw the hook toward the body member. A knob 25 is connected to the spring and hook to move the hook away from the body to release the hook from engagement with an alphabet strip. A resilient loop 26 has laterally turned ends 27 that pass through holes in the side of body member 21, the loop being disconnectable from the body member by pressing in the sides of the loop until the ends 27 clear the body member, and the loop is then withdrawn. At the hook end of body member 21 is a lug 28 that extends oppositely to knob 25 with respect to body member 21. The strip 20 has a loop at each end, one of which is engaged by hook 23 and the other by loop 26 and the strip is kept taut by spring 24.

Spaced from the under side of plate 13 is a guide rod 29 extending parallel to each longitudinal edge of the plate and having two ends secured to brackets 14 and 15. An aligning bar 30 is slidably mounted on guides 29 and has a notch in each end to receive a leg of bail 31, the bail being sufficiently resilient to permit bending it to remove the legs thereof from the slots in the aligning bar. The ends of bail 31 are pivoted at the rear ends of the members 11 and a spring 32 is connected to each leg of the bail and to the adjacent upright 16 under stress to tend to move the bail, and with it the aligning bar 30, toward the upper end of plate 13. A stop 33 is fixed on each guide 29 to limit the downward movement of aligning bar 30.

A slide 34 is mounted to move over the upper surface of plate 13 and has in it a slot 35 through which one letter on each strip 20 may be seen and thus defines a row of letters extending transversely of plate 13. A groove 36 is formed in slide 34 to receive an interrupter 37 having cut-away portions 38 through which the letters on some of the strips 20 may be seen and solid portions 39 to cover certain other strips. As many interrupters may be used as are desirable each of which has a different arrangement of cut-away portions 38 and solid portions 39 to leave some of the strips visible and cover other strips in any combination.

While but one strip 20 is shown in position on the device, it is to be understood that there may

be as many strips used as desired up to the full number of pairs of pulleys 17 and 19.

The method of operation is as follows:

Before beginning the coding of a message the bail 31 is drawn toward the operator which moves aligning bar 30 downwardly. The bar 30 is disposed to engage the lugs 28 on the strip connecting members and when further downward movement of the bar is prevented by stops 33, all of the lugs 28 will be aligned and the first letter in the alphabet sequence on each strip will be disposed under slot 35 in slide 34. The operator then rotates the pulley 17 at the left-hand side of the device to turn the first letter of the message to be coded into position under slot 35, then the second pulley 17 to bring the second letter of the message into position under the slot, the third pulley 17 to bring the third letter under the slot, and so on until each strip is so positioned that a letter thereon forms part of a word of the message in a line visible through the slot 35. Slide 34 is then moved up along plate 13 to any desired position at which a line of letters will be visible through slot 35 but inasmuch as the random sequences on the strips 20 are different, the letters then visible in slot 35 will not spell any word of the message. As shown by way of example in Figure 8, the strips 20 have been moved to spell the words "Fleet sails today" under slot 35; the slide is then moved up say thirteen letter spaces, and the meaningless sequence

DHIMORUHFIFTUVZ

appears through slot 35 as shown in the dotted line position of slide 34. This is copied as part of the code message. Another line of letters that spell the succeeding part of the message is then set under slot 35 when the slide is at the lower end of the plate. The slide is then moved up say thirteen letters and the code sequence recorded.

To decipher the message, a device must be used having strips bearing the same random sequences as the strips on the coding machine with the strips arranged in the same transverse order. The first letters of the message equal to the number of strips used are then set so that the letters of the code message appear in slot 35 with slide 34 at its lowermost position; the slide 34 is then moved up on plate 13 until there appears in slot 35 a sequence of letters that spell words in plain language, which are recorded as a part of the decoded message. This is continued until all the letters of the coded message have been converted into plain language. It is apparent that the person who decodes the message must have a key to inform him as to the arrangement on the machine of the sequences used in coding.

The coded message may be rendered still more complicated by the use of an interrupter or various interrupters under the slot 35. For example, in coding one message, or a part of one message, an interrupter having a space to leave visible the first three strips, to cover the next five strips, to leave visible four strips, to cover three strips and to show the remaining strips, may be used, and for a subsequent message, or part of a message, an interrupter that would have a different arrangement of cut-away portions and solid portions may be inserted in groove 36. In this case it is of course necessary that the person who decodes the message must know the arrangement of the cut-away portions and solid portions in the interrupter used in coding the message.

Various other means of complicating the code will suggest themselves to those skilled in the

art, such as setting the letters of the message when coding on a line other than that defined by slot 35 when slide 34 is in its lowermost position, etc.

5 It will be understood that the above description and accompanying drawings comprehend only the general and preferred embodiment of my invention and that various changes in construction, proportion and arrangement of parts 10 may be made within the scope of the appended claims without sacrificing any of the advantages of my invention.

I claim:

1. In a device of the class described, a plate, 15 supporting means therefor, a plurality of grooved pulleys at one end thereof, an equal number of grooved pulleys at the other end thereof, each of the last mentioned pulleys being disposed to coact as one member of a pair with a pulley at 20 the other end of said plate and having an outwardly extending flange whereby the pulley may be rotated, a plurality of flexible strips passing around said plate and over a pulley at each end thereof, resilient means connecting the ends of 25 each strip and having an outwardly extending lug, each said strip having on it two alphabets one above the other in the same random sequence but the sequence on each strip being different from that of any other strip, a slide movable longitudinally of said plate having a slot through 30 which a letter on each strip may be seen, an interrupter insertable in said slide to cover selectively any desired strip or strips, and means slidable longitudinally of said plate to align all of 35 said lugs.

2. In a device of the class described, a plate, supporting means therefor, a plurality of grooved pulleys at one end thereof, an equal number of grooved pulleys at the other end thereof, a plurality of flexible strips passing around said plate and over a pulley at each end thereof, each said strip having on it two alphabets one above the other in the same random sequence but the sequence on each strip being different from that on any other strip, a lug carried by each strip 40 in the same relative position, a slide movable longitudinally of said plate having a slot through which a letter on each strip may be seen, an interrupter insertable in said slide to cover selectively any desired strip or strips, and means slidable longitudinally of said plate to align all of 45 said lugs.

3. In a device of the class described, a plate, a supporting frame to hold said plate in position, 50 a plurality of grooved pulleys at one end thereof, an equal number of grooved pulleys at the other end thereof, a plurality of flexible strips passing around said plate and over a pulley at each end thereof, each said strip having on it two alphabets one above the other in the same random sequence, a slide movable longitudinally of said plate 55 having a slot through which a letter on each strip may be seen, and an interrupter insertable in said slide to cover selectively any desired strip or strips.

4. In a device of the class described, a plate, supporting means therefor, a plurality of grooved pulleys at each end thereof, a plurality of flexible strips passing around said plate and over a pulley at each end thereof, each said strip having on it an alphabet arranged in random sequence, but the sequence on each strip being different from that on any other strip, a slide movable 70 longitudinally of said plate having a slot through which a letter on each strip may be seen, and an

5

interrupter insertable in said slide to cover selectively any desired strip or strips.

5. In a device of the class described, a plate, supporting means therefor, a plurality of grooved pulleys at each end thereof, a plurality of flexible strips passing around said plate and over a pulley at each end thereof, each said strip having on it an alphabet arranged in random sequence, means to move all of said strips simultaneously to a predetermined initial position and a slide movable longitudinally of said plate having a slot through which a letter on each strip may be seen.

6. In a device of the class described, a plate, supporting means therefor, a plurality of pulleys at each end thereof, a plurality of flexible strips passing around said plate and over a pulley at

6

each end thereof, each said strip having on it an alphabet arranged in random sequence, means to move all of said strips simultaneously to a predetermined initial position and means to define a transverse line across said plate.

7. In a device of the class described having a frame, aligning means comprising parallel guides at opposite sides of said frame, a straight edge slidably mounted on said guides, a bail pivoted at its ends to opposite sides of said frame and engaging said straight edge to slide the straight edge on said guides and resilient means tending to hold said bail at one end of said frame to maintain said straight edge at said end except when moved by an operator.

JOHN W. McCLARAN.
